FOREIGN PATENT DOCUMENTS

FR 2703599 10/1994

Primary Examiner—Holly H Baynham*Assistant Examiner*—Cynthia M Chin(74) *Attorney, Agent, or Firm*—Lerner, David, Littenberg, Krumholz & Mentlik, LLP(57) **CLAIM**

The ornamental design for an interlocking toy, as shown and described.

DESCRIPTION

FIG. 1 is a perspective view of the interlocking toy in accordance with of the present invention;

FIG. 2 is a first side view of the interlocking toy of FIG. 1, the second side view being the same;

FIG. 3 is a first end view of the interlocking toy of FIG. 1, the second end view being the same;

FIG. 4 is a top view of the interlocking toy FIG. 1; and,

FIG. 5 is a bottom view of the interlocking toy of FIG. 1.
